UNITED STATES PATENT OFFICE.

LLOYD B. COGSWELL, OF WEST SPRINGFIELD, MASSACHUSETTS.

RADIO APPARATUS.

Application filed March 25, 1926. Serial No. 97,946.

My invention relates more particularly to improvements in radio-receiving apparatus, and resides in means for operating independently the shafts or axial members of 5 rotary elements, in aligning means for such axial members, and in certain peculiar controlling and limiting means for such members, together with such other parts and members and combinations of parts and 10 members as may be necessary or desirable in order to render the apparatus complete and serviceable in every respect, all as hereinafter set forth.

The primary object of my invention is to 15 provide, in radio apparatus, simple and efficient means for rotating at will in either direction any one of a number of rotor elements, such as the rotor plates of condensers and the contact arms of rheostats and potentiometers, and for grouping the actuating 20 dials in such a way that they can be conveniently operated with the digits of one hand. Heretofore it has been customary to arrange the condensers and the rheostat and 25 potentiometer, in a radio-receiving set, in such a manner that each must be operated by a dial so constructed and so remote from any other dial as to require the use of one hand for that dial alone, which rendered it 30 difficult to manipulate the dials and set the rotor elements in the act of picking up different stations and properly tuning in on the same, and consumed considerable time in so doing. These objections are removed 35 by the use of my improved operating and setting means, which can be actuated with one hand and in a minimum amount of time.

A further object is to insure accurate alignment of the axial members of a plurality of condensers arranged side by side, whereby stability and accuracy are assured.

Another object is to simplify the control and limitation of the rotor plates in a condenser, by providing a single resilient member for preventing endwise displacement of the rotor-plate shaft in its bearing, for providing the frictional resistance necessary to prevent back-lash and hold said plates in whatever position they may be left at the 50 end of the tuning in operation, and for affording a stop to limit the rotary motion of said plates in either direction.

Other objects and advantages will appear in the course of the following description.

In the present embodiment of my invention three condensers are arranged side by

side, and with them are associated a rheostat and a potentiometer, and means is provided for controlling or operating each from a convenient point in front of the panel of a 60 radio-receiving set, and all of these points of control or operation are so grouped as to make it possible to actuate independently any or all of the rotor elements with the digits of one hand, the thumb and little finger being used to operate respectively the contact arms of said potentiometer and rheostat, and the other fingers to operate the rotor plates of said condensers. Either or 65 both rheostat and potentiometer may be omitted from this grouping, in which event only the three operating dials for the condenser rotor plates are needed, and these dials will usually be operated with the same 70 three fingers as in the other case. 75

I attain the objects and secure the advantages of my invention, by the means illustrated in the accompanying drawings, in which—

Figure 1 is a top plan of a set of three condensers and a rheostat and potentiometer, and of a practical form of my operating, aligning, and controlling and limiting means, embodied with said condensers, rheostat, and potentiometer; Fig. 2, a detail, in 80 side elevation, of one of the controlling and limiting members for the rotor-plate shafts and rotor plates; Fig. 3, a longitudinal section through the axial members of two of the condensers and one of such members of 85 the third, and a vertical section through said controlling and limiting member and its associated parts; Fig. 4, a reduced, left-hand side elevation of the operating dials and of the plate therefor on the panel, the latter being in section, and, Fig. 5, a reduced front 90 elevation of said dials and plate. 95

Similar reference characters designate similar parts throughout the several views.

In the first view the operating dials are 100 positioned on their axes with their central diameters upright, and intermediate portions of said dials are broken away to disclose fully the manner in which they are mounted on the axial members of the rotor elements. The rear portions also of the large dials are 105 broken off in Fig. 1. In Fig. 2 two rotor plates are shown in the two extreme positions which are determined by the associated controlling and limiting member. A portion of the rim at the top, of each of the 110 dials appearing in Fig. 4, is broken out to

show more clearly the manner in which said rim is supported by the spokes. The dials in Fig. 4 are positioned on their axes with their central diameters horizontal, instead of vertical as in Fig. 1, said dials thus appearing as when turned forward one-fourth of a revolution from the positions which they occupy in the first view. A portion of the dial plate is broken out in Fig. 5 to bring 10 into view some of the parts behind the same and behind the panel.

It will be observed that the axes of the rotor elements here are parallel with the panel, instead of at right-angles thereto, as 15 has usually been the rule heretofore.

A front panel and a base, of a radio-receiving set, are respectively represented at 1 and 2. In the panel 1 is an opening 3. Mounted on the base 2 is a horizontal plate 20 4 from which rise three brackets 5. The plate 4 is rigidly secured to the base 2, and the brackets 5 are rigidly secured to said plate. In the center of the upright part of each bracket 5 is a slot 6 which opens 25 through the top of said part. Rigidly secured to the left-hand side of the left-hand bracket 5 and to the right-hand side of each of the other two brackets is a horizontal supporting plate 7, said plate being at right- 30 angles to the panel 1. Fastened to the left-hand side of the left-hand supporting plate 7 at each end thereof is an insulating block 8, and similar insulating blocks are fastened in corresponding positions to the right-hand 35 side of each of the other supporting plates. Extending to the left from the left-hand blocks 8 are two arms 9 between and rigidly attached to which is a set of stator plates 10. Similar arms 9 extend to the right from the 40 insulating blocks 8 attached to each of the other two plates 7, and between the arms in each of these two pairs is a corresponding set of stator plates 10. Associated with each of these three sets of stator plates 10 is a set 45 of rotor plates 11.

An externally screw-threaded bearing 12 is tapped into each supporting plate 7 at the top intermediate of the ends thereof, and securely held in place by means of a pair 50 of lock-nuts 13, one on each side of said plate. Journaled in each bearing 12 is a hollow shaft 14, and mounted on and secured to said shaft are the hubs of one of the three sets of rotor plates 11, said hubs 55 having spacers or separators 15 between them as is customary. Also mounted on and secured to each shaft 14, between the bearing 12 in which said shaft is journaled and the hubs of the rotor plates 11 mounted 60 on said shaft, is a cone 16. The end of each bearing 12, with which one of the cones 16 is contiguous, is recessed to receive the conical end of said cone in the usual manner. If desired, each shaft 14 may be provided 65 with a split-ring 17, the same being partially

received in an annular groove in said shaft, to serve as an abutment for the cone 16 on said shaft, substantially as shown in Fig. 3. The part of the cone 16 which is contiguous with the split-ring 17 is annularly channelled 70 to receive the split-ring. The adjacent ends of the left-hand and intermediate shafts 14 extend some distance beyond the bearings 12 for said shafts, to form dial-receiving projections, and the right-hand shaft 14 extends 75 to the right some distance beyond the rotor plates 11 of the right-hand condenser. The outer end of the left-hand shaft 14, beyond the rotor plates mounted thereon, is screw-threaded to receive a nut 18 which assists in 80 retaining said plates in place on said shaft, and similar provision is made at the right-hand end of the intermediate shaft 14. There is also a nut 18 on the protruding right-hand terminal of the right-hand shaft 85 14, which nut is screwed up tight against the outside of the rotor plate on said shaft, just as is done in the other two cases. This protruding, screw-threaded terminal of the right-hand shaft 14 has therein a slot 19 90 which opens through the outer end thereof. It is now evident that the rotor plates 11, in each condenser, can be moved about their common axis by rotating the shaft 14 on which said plates are mounted. 95

In order perfectly to align the three shafts 14, and at the same time provide means for rotating the right-hand shaft from a point adjacent to the protruding terminals of the other two shafts which afford means for rotating the same, I provide a rod 20 and form at the outer end thereof an enlargement or cross-head 21. The rod 20 is introduced into the outer end of the right-hand shaft 14 and pushed to the left through the intermediate shaft 14 and into the left-hand shaft 14 until the cross-head 21, which finally enters the slot 19, comes to rest against the right-hand nut 18. A nut 22 is then screwed onto the split terminal of the right-hand shaft 14 and tight against the cross-head 21, and thus prevents the rod 20 from becoming outwardly displaced. The rod 20 is, in fact, held against endwise movement 100 in either direction, since the cross-head 21 is gripped tightly between the contiguous nuts 18 and 22. Inasmuch as the rod 20 has the cross-head connection with the slotted part of the right-hand shaft 14, as just explained, the rotary motion of said rod 105 must be imparted to said shaft. A portion of the rod 20 is exposed between adjacent ends of the left-hand and intermediate shafts 14, and such portion constitutes a dial-receiving part. 110

A segmental dial 23 is provided for each of the three sets of rotor plates 11, and each dial consists of a plate, of the shape substantially as shown in Fig. 4, having its major arcuate periphery turned over on one 115 120 125 130

side to form an operating rim 24, that preferably is exteriorly knurled, and a scale-bearing flange 25 of less diameter than said rim, a hub 26, and three (more or less) 5 spokes 27 that extend from said hub to the inside of said rim for the purpose of reinforcing the same and generally stiffening the structure. After the rod 20 is passed through the right-hand shaft 14 and into 10 the intermediate shaft 14, two of the dials 23 are mounted with their hubs 26 on the dial-receiving terminals of the left-hand shaft 14 and said intermediate shaft 14, and the third dial is introduced between the 15 other two with its hub 26 in position to receive said rod, and then the latter is again pushed to the left until it passes through the middle dial hub and enters the passage in said left-hand shaft as far as it will go. 20 Each hub 26 is secured to either of the shafts 14 or to the rod 20, upon which it is mounted, by means of a set-screw 28 tapped radially into said hub and arranged in the usual manner to engage the axial member 25 within the hub. The dials are properly adjusted on their axial members before the set-screws 28 are tightened. The dials do not contact with each other at any point. The knurled rims 28 are the parts to which the 30 fingers are applied for the purpose of manipulating the dials, and are especially well adapted for that purpose.

The dials 23 in front project through the opening 13 in the panel 1, and also through 35 three slots 29 in a plate 30 which is fastened to the outer side of said panel. On both sides of the slots 29 and on the outside of the plate 30 are arcuate ribs 31, and three of these ribs, of which there are four in all, 40 are provided with horizontal indicator marks 32. The marks on the scale flanges 25 cooperate with the indicator marks 32, and it is by these marks that the dials are set and their positions determined. The arc of 45 each rib 31 is concentric with the rod 20, and corresponds in diameter with that of the scale flange 25 of the adjacent dial, and, where such rib has a mark 32 thereon, said mark is located in an advantageous position 50 relative to the marks on said flange.

Mounted on the base 2 at the right of the condensers is a rheostat generally indicated by the numeral 33, and mounted on said base at the left of the condenser is a potentiometer generally indicated by the numeral 34. The rheostat 33 has a coil 35 for which there is a contact arm 36, and the potentiometer 34 has a coil 37 for which there is a contact arm 38. The rheostat arm 36 is mounted on 55 and secured to a shaft 39 at the outer terminal thereof, and the potentiometer arm 38 is mounted on and secured to a shaft 40 at the outer terminal thereof. Extending inwardly from the panel 1, to which they are 60 secured at their front ends, are two horizontal brackets 41. The brackets 41 are on opposite sides of the dials 23 and some distance therefrom, and said brackets at their rear ends afford bearings for the shafts 39 and 40 adjacent to the inner terminal of said 65 shafts. Mounted on the terminals of the shafts 39 and 40 which project inwardly beyond the brackets 41 are two dials 42. Each dial 42, like any one of the dials 23, has a hub 26 which is slipped on to one or the 70 other of the shafts 39 and 40, and there secured by means of a set-screw 28, after the dial has been properly positioned on its shaft. With the exception of being smaller, the dials 42 are similar in practically every 75 respect to the dials 23, each of the former consisting of a plate having a major diameter which is less than the full circumference of a circle, and is turned over to form a raised operating rim 43 and a scale flange 44, 80 and reenforced with three spokes 45.

The shafts 39 and 40 are in line with each other, and located below the horizontal plane and forward of the vertical plane of the rod 20, which causes the dials 42 to be located 85 lower than the dials 23. The dials 42 are, however, made of such a size that their rims in front are tangent to the same vertical plane to which the rims of the dials 23 are tangent. The dials 42 also project through 90 the opening 3 in the panel 1, and through two slots 46 provided for them in the plate 30, on opposite sides of and extending lower than the slots 29 in said plate. Thus the dials 42 are located in convenient position to 95 be operated by the thumb and little finger while the other fingers of the same hand are operating the dials 23. The plate 30 is further provided with exterior arcuate ribs 47, two on each side of each slot 46, and on the 100 left-hand rib of each pair is a horizontal indicator mark 48 with which the marks on the adjacent dial 42 are brought into registry as the dial is operated. The arc of each rib 47 is struck from a center which is in line with 105 the axes of the shafts 39 and 40, the diameter corresponding with the diameter of the scale rim 44 of the adjacent dial, and consequently the mark 48 on any such rib is advantageously located relative to the marks on 110 the adjacent flange 44.

Any suitable arrangement of scale marks on the flanges 25 and 44 may be employed. 115

The controlling and limiting members, of which mention has been made, are associated 120 with the three cones 16, and each of said members consists of a resilient shank 49 which is attached adjacent at its lower terminal, by means of a screw 50, to one of the supporting plates 7, and has at the top a 125 fork 51 and a lug or stop 52. The screw 50 passes through the plate 7 and is tapped into the shank 49, and said shank extends upwardly from said screw and outwardly from 130 said plate into engagement with the cone 16.

above, which cone has an annular groove 53 therein to receive the fork 51 at the top of said shank. Thus the cone 16 is free to rotate, but its endwise movement is controlled by the resilient shank 49 the fork 51 of which is in the cone slot. The arm or stop 52 extends forwardly from the front edge of the fork 51, and its outer terminal is bent into the path of the nearest plate 11 of the adjacent set of rotor plates. The left-hand shank 49 is on the outside of the left-hand plate 7, while each of the other two shanks 49 is on the right-hand side of its supporting plate. The bent terminal of the left-hand stop 52 extends to the left, while the bent terminal of each of the other two stops extends to the right.

Each of the three devices just described performs the triple office of holding the cone 16 engaged thereby against the contiguous end of the bearing with which said cone is associated, and thereby preventing the shaft 14 journaled in said bearing and the rotor members mounted on and secured to said shaft from moving longitudinally in a direction away from said bearing, of holding said cone in engagement with said bearing under tension so that frictional resistance is afforded sufficient in amount to prevent back-lash when said shaft is rotated, and to hold said shaft at whatever point it may be left, and of limiting the rotation of said shaft in both directions, through the medium of the stop 52 which is in the path of one of the rotor plates 11 mounted on said shaft. The stop 52 checks the aforesaid rotor plate and with it the other rotor plate in the set, when they are actuated downwardly between the stator plates 10, as soon as the straight edges of said rotor plates are parallel with the straight edges of said stator plates, and checks the movement in the opposite direction, when said rotor plates assume a position which locates their straight edges underneath. The stop 52 thus limits the movement of the rotor plates and provides two starting points for the same.

In order to vary the tension of each shank 49, a bolt 54 is provided. The bolt 54 passes through an opening in the plate 7 to which the shank 49 is attached, and is tapped into said shank. Upon turning the bolt 54 in the direction to draw the shank 49 toward the plate 7, the tension is increased and a greater amount of friction produced between the cone 16, with which the fork 51 of said shank is engaged, and the contiguous bearing 12, and, by turning said bolt in the opposite direction, said tension is decreased and there is less frictional resistance produced between said cone and bearing. The heads of the screw 50 and the bolt 54, for each shank 49, are located in the slot 6 in the

bracket 5 to which the plate 7, supporting said shank, is attached. The head of the bolt 54 is slotted, to enable said bolt to be adjusted by means of a screw-driver as well as by means of a wrench.

In practice, the potentiometer 34 is set by manipulating the left-hand dial 42 to whatever extent may be required, with the thumb; the left-hand condenser is set by manipulating the left-hand dial 23 to whatever extent may be necessary, with the forefinger; the right-hand condenser is set by manipulating the middle dial 23 as may be needed, with the ring finger; the intermediate condenser is set by manipulating the right-hand dial 23 as needed, with the middle finger; and the rheostat 33 is set by manipulating the right-hand dial 42 as demanded with the little finger. Thus the setting of these several instruments is easily and quickly brought about simply by manipulating, with the thumb and fingers of one hand, the group of conveniently placed, five dials. The rod 20 prevents the rotor shafts of the condensers from getting out of alignment, and the combined lock, tension, and stop devices may be easily and quickly regulated, by means of their adjusting bolts 54, to provide exactly the amount of resistance required for the proper operation of said rotor plates.

More or less change in the shape, size, construction, and arrangement of some or all of the parts of this apparatus, in addition to those hereinbefore specifically pointed out, may be made without departing from the spirit of my invention, or exceeding the scope of what is claimed.

What I claim as my invention, and desire to secure by Letters Patent, is—

1. In radio apparatus, three condensers, including the same number of sets of rotor plates and shafts therefor, two of said shafts having juxtaposed terminals, bearings for said shafts, a rod secured to one of said shafts and passing through the axial center of another of said shafts into the axial center of the third shaft, and digital actuating means mounted on said juxtaposed terminals and the part of said rod which is between said terminals.

2. In radio apparatus, condensers, including rotor plates and hollow shafts for the sets of plates, one of said shafts being slotted at its outer terminal, a rod in the axial centers of said shafts, said rod having a projection in the slot in the slotted shaft, means to secure said rod with said projection in said slot, and digital operating means mounted on the exposed part of said rod and on the shaft which is unsecured to said rod.

LLOYD B. COGSWELL.
